(57) **CLAIM**

The ornamental design for the case for a cell phone, as shown and described.

DESCRIPTION

FIG. 1 is a perspective view of a case for a cell phone of my new design;

FIG. 2 is a right side view thereof, the left side view being a mirror image thereof;

FIG. 3 is a front view thereof;

FIG. 4 is a rear view thereof;

FIG. 5 is a top view thereof;

FIG. 6 is a bottom view thereof; and,

FIG. 7 is a perspective view of the case for a cell phone shown in two separated parts to show the shape and interrelationship of these two separated parts.

The broken lines depict the boundary of the unclaimed subject matter in each component.
